(57) **CLAIM**

The ornamental design for a connector unit, as shown and described.

DESCRIPTION

FIG. 1 is a top, front perspective view of a connector unit showing my new design;

FIG. 2 is a bottom, rear perspective view thereof;

FIG. 3 is a rear elevational view thereof;

FIG. 4 is a side elevational view thereof, the other side being a mirror image;

FIG. 5 is a front elevational view thereof;

FIG. 6 is a top plan view thereof; and,

FIG. 7 is a bottom view thereof.

The broken line showing of written text is for illustrative purposes only and forms no part of the claimed design.
